[57] CLAIM

The ornamental design for a lidded drum, as shown and described.

DESCRIPTION

FIG. 1 is a side elevational view of a lidded drum showing my new design;

FIG. 2 is a top plan view thereof;

FIG. 3 is a side elevational view of the lidded drum of FIG. 1, as seen from a position turned by 90°;

FIG. 4 is a bottom plan view thereof;

FIG. 5 is a top plan view of a lidded drum showing a second embodiment of my new design; the side and bottom views being identical to FIGS. 1, 3 and 4;

FIG. 6 is a top plan view showing a third embodiment of my new design; the side and bottom views being identical to FIGS. 1, 3, and 4; and,

FIG. 7 is an exploded perspective view thereof.
